NEWSPAPER FILE

George A. McDonald, Pasadena, Calif.

Application November 16, 1940, Serial No. 365,871

7 Claims. (CL. 129—4)

My invention relates to newspaper files, and more particularly to an improved file or holder for newspapers whereby they can be conveniently and firmly held for quick and ready reference, whether to refer to a reading article on some page therein, or to the advertising columns, said newspapers being held in open flat and orderly condition, one upon the other, in chronological order.

Among the salient objects of my invention are: to provide a newspaper file in which newspapers can be firmly clamped together, one upon the other, at their fold edge, with supporting means therefor, whereby said papers can be thrown back to expose other papers thereunder, and so arranged that the papers thrown back will remain back instead of rolling down again in place, as is usually the case where the top papers are thrown back; to provide in a newspaper file or holder means for holding the clamping and holding means in an inclined position, whereby to facilitate the turning of top papers back sufficiently to expose the full margin at the edge in the clamp, and also to cause said turned-back papers to remain back in out-of-the-way position; to provide in a newspaper file, in combination with suitable sharp prongs on which to impale newspapers in the manner referred to, clamping bars to be placed over said prongs, with means for locking said bars together in clamping position and for protecting the points of said prongs; to provide simple and practical means for locking and releasing the clamping bars whereby to conveniently add or to remove newspapers from the holding prongs on which they are impaled; and, in general, to provide a simple, practical and convenient newspaper file or holder which can be handled for reference purposes, and which can be stored away in a convenient and accessible place when desired for use.

In order to explain my invention, I have illustrated the same on the accompanying sheet of drawings in which:

Figure 1 is a plan view looking down on a newspaper file embodying my invention;

Figure 2 is an enlarged sectional view taken on the line 2—2 of Fig. 1;

Figure 3 is an enlarged, fragmentary front view of the device shown in Figs. 1 and 2;

Figure 4 is a fragmentary sectional view taken on the line 4—4 of Fig. 3;

Figure 5 is a detailed sectional view taken on line 5—5 of Fig. 3;

Figure 6 is a detailed view, partly in section, of a modified form of top bar or member, whereby

the clamping mechanism, apart from the base, can be handled and hung upon a rack;

Figure 7 is a vertical sectional view through a modified form of my invention, in which the top bar or member is done away with and the sharp prongs are movable back against the base member for protection.

In Figs. 1, 2, 3 and 4, I have shown my invention mounted on a base 8, having an upright left hand side 9, with two angle plates 10, 10, secured thereto, in the angle, as clearly indicated.

Rigidly secured to said plates, 10, 10, is a member or bar 11, provided with a plurality of long, sharp prongs, 12, 12, on which newspapers can be impaled, as indicated, to rest down upon said bar 11, and extend out to the right flatwise upon the base 8, as seen in Fig. 2. Pivotaly connected into the end of said bar or member 11, is a screw member 13, having thereon a knurled nut 14 and having its free end provided with a ball or head 15. One of these screw members 13 is connected into each end of said bar 11, as seen in Fig. 1.

A second or clamp bar or member 16 is provided to be placed down over said sharp prongs and to rest upon the newspapers impaled thereon, for clamping said newspapers at their fold edge or margin and so as to leave the reading column free and exposed. Said second bar or member 16 is provided at each end with a flat seat to receive the knurled nut 14, as seen at 16', Fig. 3, whereby when said nut 14 is screwed down upon said bar 16, it will be firmly clamped down upon the papers. The member or bar 11, where it engages said angle plates 10, 10, is recessed so as to fit down over said plates, as at 10' in Fig. 3.

In order to protect the sharp points of the prongs 12, I have provided a third bar or member 17, having holes or seats therein to receive said points, and in said holes I have placed a lead 40 filler, as 18, of softer material, whereby to avoid injury to said sharp points. This is shown in Fig. 4. It will be understood, of course, that the bar or member 11, in which the prongs 12, 12, are secured, is rigid and said prongs are held in one fixed position.

An important feature of my invention, is the mounting of said prongs in an inclined position, as clearly illustrated in Figs. 2 and 4. The reason for this is that the newspapers P, when thrown over to the left, as indicated in light broken lines, will remain in this position and will not roll back again over and upon the one that is being read or inspected, as would be the case if said prongs were in a vertical position. The newspapers are turned over the left hand side member 9, and fall

down outside of this side member 9, as seen in light broken lines in Fig. 2, and will remain there until turned back by hand.

Referring now to Fig. 6, I have shown a type of top bar or member, corresponding to bar 11, but made longer so as to provide opposite ends by means of which a clamping or paper holding mechanism, without the base structure 8, can be handled and hung upon any suitable paper racks, various kinds of which are in use. This bar is designated 17' and on its under side, at each end, is provided with a recess 18, of channel form, and terminating in a socket 19 to receive the hooked end 20, of a screw bolt 21, similar in other respects to the screw members 13, in the other figures. This provides means for connecting the hooked end 20 of a pivoted screw member or bolt 21, to the top, point-protecting bar 17, or 17' in Fig. 6, and provides the extension ends for hanging the holder on a rack.

It will be noted that in all these forms of my invention, when assembled, as shown in Figs. 1, 2, and 3, and the pivoted screw bolts 13, 13, are in place, and the knurled nut 14 screwed down, that all three of the bars or members 11, 16 and 17, are firmly clamped together. The clamp bar or member 16 is forced down upon the papers P, by the nut 14, and the point-protecting bar 17, or 17', as the case may be, is locked in place by the ball heads 15, 15, at the upper ends of said screw members 13, or by the hooked end 20, of the form shown in Fig. 6. The bars 16 and 17 have open slots in their ends to receive the screw-bolts 13, 13, as clearly shown. When the nut 14 is loosened, it not only releases the clamp bar 16, but it permits the screw bolt or member 13 to be swung out to the left, as indicated in light broken lines at the left of Fig. 3, and this permits the point-protecting bar 17 to be removed, and also permits the clamp bar 16 to be removed from the prongs so as to add newspapers, or to remove papers therefrom.

In Fig. 7, I have shown a modified form of my invention in which the prong carrying bar 22 is rotatably mounted in folded over ends of the angle plates, designated 18', as at 23, with a thumb screw 24, for tightening the friction on said bar 22, whereby it is possible to turn said prong-carrying bar 22 to move said prongs to upright, or vertical positions, to receive papers, or to turn them back against the side member, designated 9', in small recesses 25, provided therein to shield said sharp points, on the prongs 12' in this form or embodiment of the invention. The clamp bar 16 and the nut 14 are the same in this form of the invention, as in the other embodiments thereof shown.

In the side member 9, at the side of the base 8, it will be seen that I have provided a cut-out hand recess 26 for convenience in handling the file as a whole. It will also be seen that the file can be handled much like a drawer and can be inserted into slideways, as is a drawer, thus making it possible to have many of them in small storage space under a counter, or other receiving rack therefor.

Thus I have provided a most practical and durable newspaper file or holder in which newspapers, which are of low tensile strength, can be held in flat and usable condition. The base can be of "Celotex" or other light, suitable material, and the bars or members can be made of steel, brass, or other suitable material, as may be desired for the particular usage to which they are to be put.

It will be noted that the inclined position of the receiving prongs, which are inserted through the newspapers at the left hand margin, leaves the left margin of the reading material clearly visible, and that the inclined position of the clamping mechanism also makes possible the convenient turning of the papers over to the left, as seen in light broken lines in Fig. 2, out of the way and where they will remain until replaced by hand, which is not the case where the holding members hold the bound edges of the papers in a vertical position.

I am aware that changes in details of construction and arrangement can be made without departing from the spirit of my invention, and I do not, therefore, limit the invention to the showing made for explanatory purposes, except as I may be limited by the hereto appended claims.

I claim:

20. A newspaper file including a member having a plurality of impaling prongs secured therein to receive papers thereon, a second member adapted to be placed over said prongs, upon said papers, to clamp said papers to said first member, clamping means connecting the opposite ends of said members for tightening them upon said papers, and a third member adapted to be placed over the points of said prongs to protect them, the clamping means connecting the opposite ends of said first members being adapted to secure said third member in place on the points of said prongs.

25. A newspaper file of the character referred to including a base with a side member, a member mounted thereon and having a plurality of impaling prongs secured to said member and inclined toward said side member, a member adapted to be placed on said prongs, for clamping newspapers therebetween, a screw bolt at each end of said members with a nut thereon for tightening said last named member down upon said first named member, with newspapers therebetween, and a third member adapted to be placed upon the upper ends of said prongs to cover their sharp ends, said screw bolts being adapted to secure said third member in position on said prongs.

30. A newspaper file including in combination a member having prongs projecting therefrom on which to impale newspapers, a second member adapted to be placed on said prongs, on newspapers thereon, a third member adapted to be placed on the sharp ends of said prongs to prevent accidental engagement therewith, and screw bolts connecting the ends of said first and third members and having nuts thereon adapted to be screwed down upon said second member to clamp it on to said first member, with newspapers therebetween.

35. A newspaper file including in combination a member having prongs projecting therefrom on which to impale newspapers, a second member adapted to be placed on said prongs, on newspapers thereon, a third member adapted to be placed on the sharp ends of said prongs to prevent accidental engagement therewith, and screw bolts pivotally connected at one end with said first member and each having means at its other end to connect with said third member for holding it in place, and a nut on each of said screw bolts adapted to be screwed down upon the opposite ends of said second member to clamp it upon said first member, with newspapers therebetween.

40. A newspaper file including in combination a member having prongs projecting therefrom on which to impale newspapers, a second member adapted to be placed on said prongs, on news-

papers thereon, a third member adapted to be placed on the sharp ends of said prongs to prevent accidental engagement therewith, screw bolts pivotally connected to one of said members and adapted to be moved into engagement with the other two of said members for interlocking all three of said members together in holding relationship with newspapers clamped therebetween.

6. A newspaper file including a flat base to receive newspapers flat wise thereupon, a rigid side member along one side thereof forming an angle therewith, a plurality of impaling prongs having their lower ends anchored to said base and extending upwardly in an inclined position toward the upper edge of said side member, the upper ends of said prongs being sharp to pierce papers as they are placed on said prongs, a bar movable on said prongs for clamping newspapers together at their attached edges, whereby said newspapers can be turned back over said inclined prongs and over the top edge of said side member at an angle

of rest to prevent return of said newspapers by gravity to flat position on said base.

7. In a newspaper file, a flat base member, a bar mounted thereon and having a plurality of prongs projecting therefrom at an angle for impaling newspapers thereon down upon said bar, a side member along one side of said base, forming an angle therewith across which said impaling prongs are inclined from said base toward the upper edge of said side member, a clamping bar upon said prongs for clamping newspapers down upon said first bar, and means for tightening said clamping bar upon said papers, said clamping bar normally resting to one side of said first bar on said prongs, whereby newspapers impaled on said prongs and held between said bars, can be turned back over said second bar and said impaling prongs to an angle of rest to prevent their falling back by gravity upon said base.

GEORGE A. McDONALD.
